JOSEPH H. CRANFORD, OF WASHINGTON, DISTRICT OF COLUMBIA, ASSIGNOR TO SIMPLEX CONCRETE PILING COMPANY, OF WASHINGTON, DISTRICT OF COLUMBIA, A CORPORATION OF THE DISTRICT OF COLUMBIA.

PILE AND METHOD OF MAKING THE SAME.

969,136.

Specification of Letters Patent. Patented Aug. 30, 1916.

Application filed June 29, 1905, Serial No. 267,651. Renewed January 28, 1910. Serial No. 540,698.

To all whom it may concern:

Be it known that I, JOSEPH H. CRANFORD, a citizen of the United States, and a resident of Washington, District of Columbia, have 5 invented certain Improvements in Piles and the Method of Making Same, of which the following is a specification.

My invention consists of a composite pile partly of wood and partly of concrete, these 10 two members of the pile being so disposed that the entire pile can be put in with a much shorter pile-driver, and in a much more convenient manner than if the entire pile was either of wood or of concrete.

15 In tropical waters, that portion of a wooden pile from some three feet under the bottom of the water to the high water line, is subject to rapid deterioration or destruction, sometimes by rot, and sometimes by the 20 attack of the teredo or other wood-destroying animals or insects. By making of concrete the portion exposed to these attacks, the pile will last a very long time, as the wooden portion, being entirely buried, can 25 not be acted upon by these destructive agencies.

In the case of piles for foundations of 30 buildings or other structures on land near water, it is always necessary to saw the wooden pile off to a point below the permanent water line, as the wooden pile, if subjected to alternate wetting and drying, will 35 very quickly rot. It therefore, becomes necessary to first drive the wooden pile down to the ground line, then to excavate down to a point below the permanent water line and then fill up with concrete or other building 40 material. This excavation and filling up is very expensive, but by making that portion of the pile above the permanent water line 45 of concrete, such excavation and filling become unnecessary, and obvious economies result.

In the accompanying drawing:—Figure 1, 45 is a view showing the wooden pile driven into the ground, the cap being in section; Fig. 2, is a view of the wooden and tubular pile driven into the ground; and Figs. 3 and 4, are sectional views of the finished 50 pile.

In carrying out my invention, I make a composite pile, the lower portion of which is of wood and the upper portion of concrete so that any desired portion of the total

length of the pile can be composed of concrete, the wooden portion being driven so deeply into the ground as to be free from alternate wetting and drying, such as would cause it to rot, while the concrete upper member of the pile will be of such a depth 55 that in under-water work it will be the only portion of the pile contained in the water or soft bottom of the waterway, hence the pile will be free from injury caused by the ravages of wood-destroying or other insect or 60 animal life.

In carrying out my invention, I first prepare a wooden pile 1, of a length appropriate for this member of the composite pile and drive the same into the ground until its 70 top approaches the surface of the ground, as shown in Fig. 1, the pile being provided with an appropriate metal cap 2. Either before the driving operation, or after the wooden pile has been thus driven, the lower 75 end of a tubular pile 3, is fitted to the cap 2, this pile serving as the medium whereby the wooden pile 1 and its cap 2 can be driven still farther into the ground, such operation being continued until the wooden pile 80 reaches its proper depth, as shown in Fig. 2. Before commencing this secondary driving operation, a dowel pin 4, preferably consisting of a metal rod or tube, is driven into the upper end of the pile, or inserted into an 85 opening therein previously prepared for its reception, a portion of this dowel pin projecting above the wooden pile 1 and its cap 2, as shown in Fig. 2.

The dowel pin 4 aids in uniting the two 90 members of the pile and strengthens the joint between the two, so as to prevent lateral strains upon the concrete member of the pile from causing the latter to break away from the cap 2 of the wooden member, the 95 composite pile being therefore, perfectly rigid throughout all portions of its length. A plurality of dowels, can be used or mechanical equivalents substituted for the same, in order to properly connect the two members and form a pile which is rigid throughout.

I place within the hollow pile 3, either before or after the driving of the same, a thin sheet-metal tube 6, which is permitted to retain its place when the hollow pile is withdrawn, and serves as a retaining casing or mold for the concrete member of the pile.

Preferably this interior tube or casing, while extending below the soft bottom of the water-way, does not extend to the bottom of the hollow pile 3, (see Fig. 4) so that the 5 concrete below the lower end of the tube 6 expands to the full diameter of the bore of the opening formed by the cap 2, as shown at 7 in Fig. 2, and thus provides for a better hold of the concrete member of the pile upon 10 the soil at the bottom of the water-way than would be possible if the casing 6 extended all the way down to the cap 2.

In piles of this class, and in fact in all 15 piles in which the concrete member is subjected to a lateral strain I prefer to embed in said concrete member a metallic reinforce, preferably in the form of a wire cage or grating 8, such as shown in Fig. 2, this cage or grating being introduced into the preparatory pile before or after the driving of 20 the same, and the subsequently introduced concrete being forced through the meshes of the cage or grating, so that the latter will be firmly embedded therein, and will properly 25 strengthen or stiffen the same. The hollow pile 3 is now withdrawn either slowly or intermittently, and during such withdrawal concrete is fed through it into the opening formed above the pile 1 and suitably 30 rammed therein, so that by the time the hollow pile 3 is fully withdrawn the concrete member 5 of the pile will extend from the top of the wooden pile 1 to the surface of the ground. The entire pile 3 can be filled with 35 soft concrete and then withdrawn, leaving the concrete in the ground to set and form the upper portion of the composite pile, or said pile 3 can be withdrawn before filling in the concrete, in which case it is not necessary 40 that it should be hollow.

My improved composite pile, can be set by means of a pile driver whose height is determined by the length of a single member of the pile instead of by its total length, 45 so that very long piles can be set by the pile drivers, and while the composite pile is quite as effective for many purposes as one made wholly of concrete, it is cheaper than the latter, or even than a long wooden pile, 50 and the formation of the relatively short concrete member 5 of the pile can be effected in correspondingly less time than the formation of a full length concrete pile, these advantages in addition to the others noted, 55 rendering my composite pile more acceptable

for many uses than a long wooden pile or than a pile made wholly of concrete.

If piles are to be placed in sand or sandy soil, sinking instead of driving may be resorted to, that is to say, the sand or sandy soil may be displaced in advance of the pile 1 by means of a water jet, and said pile and the pile 3 permitted to sink to the desired position by reason of such displacement, aided, if need be, by the blows of a hammer. 60 65

Having thus described my invention, I claim and desire to secure by Letters Patent:—

1. The mode herein described of making piles, said mode consisting in driving a 70 wooden pile to a point below the surface of the ground by means of a superposed hollow pile, providing the latter with an internal metallic casing and then withdrawing the hollow pile and filling concrete into the 75 casing, such concrete structure forming a continuation of the wooden pile, substantially as specified.

2. The mode herein described of forming a pile, said mode consisting in driving a 80 wooden pile to a point below the surface of the ground by means of a superposed hollow pile, providing said hollow pile with an internal metallic casing which does not extend to the bottom of the same, and then 85 withdrawing said hollow pile and filling concrete into the internal casing and into the expanded opening below the same caused by the withdrawal of the hollow pile so that said concrete structure will form a 90 continuation of the wooden pile, substantially as specified.

3. The mode herein described of forming a pile, said mode consisting in driving a 95 wooden pile to a point below the surface of the ground by means of a superposed hollow pile, inserting in the latter a metal casing and a metallic reinforce, and then withdrawing the hollow pile and feeding concrete into the said metallic casing and causing 100 it to engage with said metallic reinforce therein, substantially as specified.

In testimony whereof, I have signed my name to this specification, in the presence of two subscribing witnesses.

JOSEPH H. CRANFORD
